The ornamental design for a ski training machine, as shown and described.

DESCRIPTION

FIG. 1 is a front, right-side perspective view showing my new design, wherein the front, left-side perspective view is a mirror image thereof;

FIG. 2 is front elevation view thereof;

FIG. 3 is a back elevation view thereof;

FIG. 4 is a right-side elevation view thereof;

FIG. 5 is a left-side elevation view thereof;

FIG. 6 is a top view thereof;

FIG. 7 is a bottom view thereof;

FIG. 8 is a front, right-side perspective view showing my new design disposed on an optional support structure, wherein the front, left-side perspective view is a mirror image thereof;

FIG. 9 is a front elevation view thereof;

FIG. 10 is a back elevation view thereof;

FIG. 11 is a right-side elevation view thereof;

FIG. 12 is a left-side elevation view thereof;

FIG. 13 is a top view thereof; and,

FIG. 14 is a bottom view of the optional support structure. The broken lines illustrate portions of the ski training machine which form no part of the claimed design.

Environmental matter is shown with a symbolic break, for the purposes of scale.
